UNITED STATES PATENT OFFICE.

EDWARD P. SHELDON, OF NEW YORK, N. Y., ASSIGNEE TO R. HOE AND CO., OF NEW YORK, N. Y., A CORPORATION OF NEW YORK.

DELIVERY MECHANISM FOR FOLDED PRODUCTS.

1,336,445.

Specification of Letters Patent.

Patented Apr. 13, 1920.

Original application filed February 2, 1910, Serial No. 541,447. Patent No. 1,116,513, dated November 24, 1914. Divided and this application filed July 27, 1911. Serial No. 640,731.

To all whom it may concern:

Be it known that I, EDWARD P. SHELDON, a citizen of the United States, residing at New York, county of Kings, and State of

5 New York, have invented certain new and useful Improvements in Delivery Mechanism for Folded Products, fully described and represented in the following specification and the accompanying drawings, forming a part of the same.

This invention relates to improvements in machines for producing a folded product.

In producing folded products, such, for instance, as weekly papers, or magazines

15 comprising a large number of plies constituting what may be termed a single signature, it is customary either to apply the cover and the inset advertising sheets, when they are used, in the printing machine by

20 agencies connected directly with the printing machine, in which case the product is usually secured together by stapling or otherwise by agencies forming a part of the printing machine, or the main part of the

25 product is produced in the printing machine and the inset sheet and cover or both are applied after the product is taken from the printing machine, in which case the securing of the plies together is effected outside

30 of the printing machine. Further, in the production of the products referred to, it is customary, after the product is completed, to trim the ends and sides of the product, this being accomplished by an independent

35 trimming machine.

It is one of the objects of this invention to produce an improved machine for producing a folded product provided with a delivery mechanism which includes devices

40 by which the product may be trimmed, and a second delivery mechanism which receives the product in an untrimmed condition, the mechanism including means by which either delivery mechanism may be utilized.

45 A further object of the invention is to produce an improved trimming mechanism which may be employed in connection with machines for producing a folded product, said mechanism embodying devices by which

50 the edge of the product opposite the fold line may be trimmed.

With these and other objects not specifically referred to in view, the invention consists in certain constructions and in cer-

tain parts, improvements and combinations 55 as will be hereinafter fully described and then specifically pointed out.

Referring to the drawings—

Figure 1 is an end view, partly in section, of one form of mechanism embodying the 60 invention, this mechanism being shown in connection with the product assembling mechanism of a fast rotary printing machine.

Fig. 2 is an end elevation, partly in section, 65 of the construction shown in Fig. 1, the product assembling mechanism of the printing machine being omitted from this view.

Fig. 3 is a detail, partly in section, of 70 the clamping mechanism which is employed to hold the sheets while they are being trimmed.

Constructions embodying the invention are particularly adapted for use with the 75 product assembling devices of fast rotary printing machines, although the invention is not restricted to such use.

In the particular construction illustrated, 1 indicates the drawing-off rolls ordinarily 80 employed in a printing machine for assembling a number of printed webs. From these drawing off rolls, the webs, in the construction illustrated, pass between the usual cutting cylinders 2 by which the webs are 85 divided into sheets.

The particular machine in connection with which the invention is illustrated, is intended to insert what is called an inset sheet. Provision is made for the addition to 90 the sheets taken from the cutters 2, of a sheet or sheets formed by cutters 3, this sheet passing between advancing rolls 4 and beneath a roll 5, this product being assembled with the product from the rolls 2 95 by rolls 6.

The particular machine illustrated is also provided with cover supplying means, the cover being assembled with the product passing between the rolls 6 by means of rolls 100 7 and a roll 7.

The particular machine illustrated is also provided with means for securing together the various plies which form the product. As shown, the plies are secured together by 105 staples which are inserted by a stapling roll 8 co-operating with one of the rolls 7 before referred to.

As illustrated, the product after leaving the rolls 7, 8, passes in a flat form between the rolls 9, and is forwarded by tapes 10 passing around the rolls 9 and 11 beneath a transverse folding knife, as indicated at 12.

It will be understood that the devices so far described are of usual form, and that other devices may be substituted for some or all of them, if desired, those illustrated being selected merely to illustrate a form of mechanism for producing a folded product.

When the invention is carried into effect in connection with a mechanism for producing a folded product, the product may be forwarded from the folding mechanism to a delivery mechanism including trimming devices. In the particular machine shown, the transverse folding knife before referred to passes the product into the nip of a pair of folding rolls 13 which rolls deliver the product to a guide 14 which in turn directs the product to a set of forwarding tapes 15, 16. The tapes 15 pass around supporting rolls or pulleys 17, 18, 19, 20, 21 and 22, and the tapes 16 pass around rolls or pulleys 23, 24, 25, 26, the pulley 19 before referred to and a roll 27. These tapes constitute a well-known type of forwarding device for the product, but it is to be understood that any other suitable form of forwarding device may be used instead of them.

In the particular machine shown, the forwarding devices conduct the product past suitable trimming mechanism which operates to trim the ends of the product. While this trimming mechanism may be varied in character, as shown, it consists of rotary slitting knives 28 which coöperate with the roll 19 before referred to. This roll 19 may be a driven roll, and in the construction illustrated is shown as driven by an intermediate 29 from a gear 30, this gear being in mesh with a gear 31 on a shaft 32. This shaft 32 when employed may be driven in any suitable manner. As illustrated, it is provided with a gear 33 in mesh with a gear 34 on a shaft 35, this shaft being driven from a way shaft 36 by means of the usual bevel gears 37, 38. The shaft 36 may be driven from a shaft 39 which may constitute the power shaft of the mechanism, by means of intermeshing gears 40, 41.

When the invention is embodied in a machine which includes end trimming devices, the product may, after it has been acted upon by these devices, be subjected to the action of mechanism by which the trimming of the edge of the product opposite the folded edge is effected.

The edge trimming mechanism employed may be varied widely. As illustrated, the product, after passing between the tapes and the rolls 20, 26, is delivered upon a table 48, a guide 49 being, in the machine illus-

trated, shown as operating in connection with the rolls to insure the proper delivery of the product upon the table. In machines embodying the invention in its best form a registering device will be employed to properly position the product with respect to the edge trimming devices. Where, as in the machine illustrated, the trimming devices include a support or table upon which the product is brought to a stop before trimming, the registering device may include a series of swinging stops 50, these stops being mounted on a rock shaft 51 which may be operated through a rock arm 52 and a rod 53, this rod being actuated by a suitable cam which may be driven from a gear 56 in mesh with a gear 57 on the shaft 32, such actuating mechanism being common. It will be understood, of course, that by the mechanism referred to the stops will be interposed in the path of the product at the proper time to stop it, so that the edge to be trimmed will be properly presented to the trimming devices.

The trimming devices may include a knife 58 secured to a cross-head 60. The knife may coöperate with a cutter block 62 mounted on a cross bar 63, this bar also serving to support the table 48 before referred to. The cutter may be operated by means of rods 64 from cams in disks 67. A suitable clamp may be employed to hold the sheets while the carrier is operated, as usual in such constructions.

The particular construction of this clamping mechanism may be varied, but as illustrated there is provided a clamping bar 74, this bar being carried by spring plungers 80 mounted in the cutter cross-head 60. This clamping bar is brought into operation by the descent of the cutter-head and firmly holds the edge opposite the fold line during the trimming operation.

When the edge trimming means employed is of such a character that the product is stopped in order to effect the trimming, means may be provided for again forwarding the product after trimming. While the means employed may be varied in character, as shown, there is provided a series of forwarding rolls 81 mounted on a shaft 82, this shaft being preferably continuously driven in any suitable manner, as, for instance, by a gear 83 loosely mounted on the shaft 51 before referred to, this gear being in turn driven from suitable gearing on shafts 84 which carry, in the machine illustrated, directing rolls 84'. A guide 85 may be employed in connection with these directing rolls. The usual drop rolls may be employed to hold the sheets against the forwarding rolls 81.

The product having been trimmed and set in motion may be delivered in any suitable manner. In the construction shown, the

rolls 84' deliver to the usual S-fly 92 which in turn drops it on a conveyer 93 of the usual type.

Machines embodying the invention in its best form will include a second delivery mechanism which does not embody trimming devices. In the construction illustrated, the guide 14 is formed as a switch and may be set so that the product coming from the rolls 13 instead of being delivered to the advancing devices before described, may be delivered directly to an S-fly 94 which in turn delivers the product to the conveyer 93.

The trimming mechanism for effecting the trimming herein described and particularly illustrated contains certain novel features which are not herein claimed as they are claimed in application Serial No. 541,447, filed February 2, 1910, of which this application is a division.

Changes and variations may be made in the construction by which the invention is carried into effect. The invention is not, therefore, to be confined to the particular constructions herein shown and described.

What is claimed is:—

1. The combination with means for producing a folded product, said means including devices for securing the plies together at the fold line, of a delivery mechanism arranged to handle the entire product, a second delivery mechanism also arranged to

handle the entire product and including devices for trimming the product opposite the fold line after its final fold, and means for 35 directing the product to either delivery mechanism.

2. The combination with means for producing a folded product, said means including devices for securing the plies together at 40 the fold line, of a delivery mechanism, a second delivery mechanism including devices for trimming the ends and side of the product, and means for directing the product to either delivery mechanism.

3. The combination with means for producing a folded product stapled together at its fold line, of forwarding means, and means for trimming the edge of the folded product opposite the fold line after the fold. 50

4. The combination with means for producing a group of folded plies stitched together at the fold line, of forwarding means, and means acting subsequent to the folding means for trimming at one operation the 55 edges of the plies opposite to the fold line.

In testimony whereof I have hereunto set my hand, in the presence of two subscribing witnesses.

EDWARD P. SHELDON.
